Primary Examiner — Philip S Hyder*(74) Attorney, Agent, or Firm* — Boudwin Intellectual Property; Daniel Boudwin(57) **CLAIM**

The ornamental design for a drywall sanding sponge, as shown and described.

DESCRIPTION

FIG. 1 depicts a perspective view of the drywall sanding sponge.

FIG. 2 depicts a front elevation view of the drywall sanding sponge.

FIG. 3 depicts a rear elevation view of the drywall sanding sponge.

FIG. 4 depicts a left elevation view of the drywall sanding sponge.

FIG. 5 depicts a right elevation view of the drywall sanding sponge.

FIG. 6 depicts a top plan view of the drywall sanding sponge; and,

FIG. 7 depicts a bottom plan view of the drywall sanding sponge.

The shade lines in the Figures show contour and not surface ornamentation.

The broken lines in the Figures form no part of the claimed design.

1 Claim, 4 Drawing Sheets(56)
